UNITED STATES PATENT OFFICE.

HARRISON M. BRIGHTMAN, OF COLUMBUS, OHIO, ASSIGNEE OF ONE-FOURTH TO G. F. BRIGHTMAN, ONE-FOURTH TO H. L. BRIGHTMAN, AND ONE-FOURTH TO J. H. BRIGHTMAN, ALL OF COLUMBUS, OHIO.

CONVEYER APPARATUS.

Application filed January 3, 1922. Serial No. 526,787.

To all whom it may concern:

Be it known that I, HARRISON M. BRIGHTMAN, a citizen of the United States of America, residing at Columbus, in the county of 5 Franklin and State of Ohio, have invented certain new and useful Improvements in Conveyer Apparatus, of which the following is a specification.

My present invention relates generally to 10 conveyors and more particularly to traversing hoists capable of utilization as loading and unloading devices as well as for various other purposes, my object being the provision of an apparatus for general use, inside as well 15 as outside, in connection with factories, buildings and the like, which is capable of receiving its power from various sources including electrical motors and which may be manually controlled at various points in 20 its length in both its load lifting and load carrying operations.

A further object of my present invention as well as the resulting advantages thereof will be more fully brought out and more 25 readily understood by reference to the accompanying description referring to the drawings illustrating the invention, the latter of which includes several figures of which,

30 Figure 1 is a diagrammatic plan view of the complete apparatus,

Figure 2 is a diagrammatic side view,

35 Figure 3 is a partial side view, on an enlarged scale, of a portion of the overhead track and the carrier movable thereon,

Figure 4 is a sectional top plan view of the parts shown in Figure 3,

40 Figures 5 and 6 are detail vertical transverse sections taken respectively on lines 5—5 and 6—6 of Figure 3,

Figure 7 is a detail vertical transverse section showing one of the hoist connection supporting brackets shifted laterally away from this normal position,

45 Figure 8 is a rear elevation of the clutch and brake controlled driven connections,

Figure 9 is a top plan view of the parts shown in Figure 8,

50 Figure 10, is a side elevation of the same parts,

Figure 11 is a vertical sectional view through the brake device taken substantially on line 11—11 of Figure 12, and

Figure 12 is a rear elevation of the brake device.

Referring now to these figures and particularly to Figures 1 and 2, I have shown a continuously driven actuating shaft 15 supported in bearings 16 in connection with supporting uprights 17 and driven in any suitable manner as by means of gears 18 and 19 from an electric motor 20. Shaft 15 has fast thereon a series of pulleys arranged in pairs 21 and 22, the two pulleys of the pair 21 receiving thereon a straight belt 23 and a twisted belt 24 while the pulleys of the pair 22 receive a straight belt 25 and a twisted belt 26.

The belts 23 and 24, extending around the pulleys 21 of shaft 15, are for the purpose of respectively driving pulleys 27 and 28 of a shaft 29, said pulleys 27 and 28 being normally loose on shaft 29 and adapted to be engaged therewith under control of clutches in turn controlled by a clutch lever 30 so that 70 considering the flat and twisted belts 23 and 24 it is obvious that lever 30 upon movement in one direction serves to engage pulley 27 with the shaft 29 while upon its movement in the opposite direction it serves to engage pulley 28 with shaft 29. The clutch control lever 30 is shown in neutral position in Figure 1, both pulleys 27 and 28 rotating freely on the shaft 29.

The shaft 29 is journaled in bearings 31 85 in one side upright 32 and a central upright 33 of a supporting frame which frame has in addition to these uprights, another side upright 34 as particularly seen in Figures 8 and 9, this frame being located at one end 90 of the apparatus proposed by my invention parallel in a position with, and in adjacent though spaced relation to, the uprights 17 supporting the driving shaft 15.

As seen furthermore in Figures 8 and 9 95 the shaft 29 drives, through gears 35 and 36 and through a countershaft 37, a drum shaft 38 for certain hoisting connections, which may have winding drums 39 thereon and which is preferably journaled across the three uprights 32, 33 and 34.

The clutch control shaft 29 is furthermore provided with a brake device including a brake drum 40 keyed thereon as best seen in Figures 11 and 12, a flexible band 41 extending around this drum and serving as the

brake element. This brake is controlled by virtue of the extension of the end of the brake band 41 between a pair of disks 42 mounted upon a brake shaft 43 and having 5 an annular series of apertures 44 through selected apertures of which pins 45 and 46 may be extended, these pins being also projected through the ends of the brake band 41 so that the latter is thus capable of 10 adjustment for wear and stretching of the brake band 41 and is at the same time capable of shifting the brake band into and out of active position upon rotative movement of the brake shaft 43. This brake 15 shaft 43 is mounted in a bearing 47 on the side upright 32 and is provided at its outer end with an apertured crank arm 48 as seen in Figures 8, 9 and 12. As also seen in Figure 9 a bracket arm 49 supports a pulley 50, 20 the latter being preferably grooved to receive therearound one end portion of an endless flexible brake actuating connection 51 the latter of which is securely fastened at one point to the crank arm 48 of the brake 25 shaft 43.

The other pair of belts 25 and 26 projecting from the driving shaft 15, extend around the pulleys 52 and 53 of a clutch control shaft 54, these pulleys 52 and 53 being engaged with the shaft 54 by virtue of clutches controlled by a clutch lever 55. As seen in Figures 8 and 9 shaft 54 is journaled across the uprights 32, 33 and 34 and is connected by gears 56 and 57, through a countershaft 58 to a driven shaft 59 having adjacent to the side uprights 32 and 34 sprocket wheels 60 around which sprocket chains 61 extend at one end so that it is obvious that upon shifting movement of the clutch lever 40 55 in one direction, pulley 52 will be engaged with shaft 54 so that the sprocket chain 60 will be moved in one direction while when the clutch lever is shifted in the opposite direction pulley 53 will be clutched with shaft 45 54 and the sprocket chains will be moved in the opposite direction.

The sprocket chains 61 extend along and above I-beams 62, each of which forms a trackway for a carrier 63 and it is thus obvious that Figure 1 shows an arrangement providing for the simultaneous operation of two carriers 63 in parallel relation so as to handle articles of considerable length although it is to be understood the invention 50 55 is in fact complete with but a single track beam 62 and a single actuating sprocket chain 61.

To this end each carrier 63 includes a frame 64 with upper inwardly projecting 60 65 stub shafts 65 (see Figure 10) at its opposite sides, supporting track engaging rollers 66 the latter of which are disposed on the lower flanges of the respective track beam 62 as shown particularly in Figure 5. It 65 will be noted from this figure and from Fig-

ures 3 and 10 that each carrier has lower transverse shafts 67 at lengthwise spaced points, on which are mounted grooved pulleys 68 receiving thereover portions of a flexible hoisting connection 69, which between the pulleys 68, pass downwardly around the pulley 70 of a fall 71 having an article engaging grapple or hook 72 as seen in Figure 2 so as to thus form article engaging and hoisting means. 70 75

One end of the flexible connection 69 extends to and around one of the hoisting drums 39 of the hoist shaft 38 and the opposite end of this hoisting connection is fixed as at 73 in Figures 1 and 2 to a wall or other support 74 to which one end of the track beam 62 may be fastened, and which support, or uprights 75 adjacent thereto, may serve as a mounting for sprocket wheels 76 around which the traverse chains 61 may be 80 85 extended. I prefer however that these sprocket wheels 76 be mounted upon a shaft 77 as seen in Figure 1.

At spaced points therealong, each track beam 62 has clamped thereto a bracket 78 one of which is shown in Figure 6, provided with outstanding bolts 79 in parallel vertically spaced relation to receive rollers 80 upon which the upper and lower runs of the respective sprocket chain 61 are movably guided. Each bracket 78 also has at its opposite side a pivoted supporting arm 81, the pivot of which is indicated at 82. This arm normally depends by gravity into the position shown in Figure 6 with its lower angular end 83 beneath the track beam 62, said lower angular end having journaled therein a concave roller 84 serving as a support for the flexible hoisting connection 69. Each supporting member or arm 81 for the hoisting connection 69 is thus swingable laterally out of the path of movement of the carrier 63 in order that the latter may pass freely along the entire length of its respective track beam 62, it being observed from Figures 3, 4 and 5 that each carrier 63 is provided with a deflecting member 85 in the nature of a side strip provided with angularly bent opposite ends 86 forwardly and rearwardly of the carrier whose function is to engage the lower free ends of the laterally swingable supporting arms 81 and shift the latter from the path of the carrier as it moves along the track beam. This shifting of the supporting arms 81 throws each thereof in turn to one side into the position shown in Figure 7, upon the pivotal connection 82 of its upper end. 100 105 110 115 120

Each of the carriers 63 is provided at one side with an upstanding angular clamping arm 87 whose upper end supports a clamping bolt 88 and engaging the lower run of the respective sprocket chain 61 as particularly shown in Figures 3, 4, 5 and 10. 125 130

The clutch lever 30 controlling movement as well as the direction of movement of the flexible hoist connection 69, is secured at 89 as in Figure 9 to one point of an end-
 5 less flexible clutch controlling connection 90 extending between and around pulleys 91 and 92 and having any desired number of portions 93 depending around pulleys 94 and 95 so as to extend downwardly at any
 10 desired points in the length of the apparatus as a whole, and as seen clearly in Figure 2 in order that by manually shifting this flexible controlling connection 90 from points near the ground, the flexible
 15 hoist connection 69 may be wound upon and unwound from the pulley 39 to respectively raise and lower the fall 71.

It will also be obvious that the brake control connection 51 may have portions ex-
 20 tending downwardly around rollers 96 and 97 as seen in Figure 2 so that from the same points from which the hoist connection is manually controlled, the brake may also be manually controlled to engage and
 25 hold the clutch control shaft 29 when both of the pulleys 27 and 28 are unclutched. The purpose of this is to avoid danger of accidental lowering of the fall 71 when the controlling clutches of the pulleys 27 and
 30 28 are disengaged.

It will also be noted by reference to Figure 9 that the clutch controlling lever 55 of the pulleys 52 and 53 of the clutch control shaft 54 is securely clamped at 98 to one
 35 point of a flexible traverse controlling connection 99 passing around pulleys 100 at respectively opposite ends of the apparatus, and having depending portions 101 extending around guide rollers 102 (see Figure
 40 2) adjacent to the depending portions providing for manual control of the flexible hoist connection 69 as well as the brake previously described. It is thus obvious that through the manual shifting of the traverse
 45 controlling connection 99, the direction of movement of the chain 61 may be readily controlled and it is furthermore obvious that on account of this particular form of manual control it is obvious that the functions of the apparatus may be directed by an operator standing at various points in
 50 the length of the apparatus.

It is furthermore obvious that considering the functions it performs and the ready
 55 manner in which it may be controlled, the apparatus as a whole is comparatively inexpensive both in first cost as well as upkeep, is capable of ready installation, and will be effective and efficient for the purposes for
 60 which it is intended.

I claim:

1. A conveyer apparatus including a horizontally movable elevated carrier having an article engaging member, and a flexible hoisting connection extending along the path of

movement of the carrier, with which the carrier has movable engagement at spaced points and with which the said article engaging member has movable engagement between the said points of engagement of said carrier, said hoisting connection being anchored at one end adjacent to one end of the path of movement of the carrier, means for controlling the hoisting connection, located at its opposite end adjacent to the opposite end of the path of movement of the carrier, including winding means for varying the effective length of the hoisting connection and a brake for holding the same in adjusted position and means extending along the path of movement of the carrier and manually shiftable at a plurality of points therealong for independently controlling action of said winding means and said brake.

2. A conveyer apparatus including a horizontally movable carrier having article engaging means movable therewith, flexible means extending along the path of movement of the carrier for moving the same and raising and lowering the said article engaging means, and means also extending along the path of movement of the carrier and manually shiftable at a plurality of points therealong for independently controlling horizontal movement of the carrier and vertical movement of said article engaging means.

3. A conveyer apparatus including a horizontally movable carrier having article engaging means movable therewith, means having controlling clutches for moving said carrier and raising and lowering the said article engaging means, and manually actuated means for independently controlling said clutches at various points along the path of movement of the carrier.

4. A conveyer apparatus including a horizontally movable carrier having article engaging means movable therewith and vertically shiftable with respect thereto, means having controlling clutches for moving said carrier and raising and lowering the said article engaging means, levers engaging the said clutches, and endless flexible controlling connections to which the said clutch levers are connected, extending along the path of movement of the carrier whereby the clutches may be manually manipulated from a plurality of points along the path of movement of the carrier independent of the latter.

5. A conveyer apparatus including a horizontally movable elevated carrier having an article engaging number movable therewith and shiftable vertically with respect thereto, an endless movable member to which the carrier is connected, a flexible hoisting connection extending along the path of movement of the carrier and on which the article engaging member is supported for move-

4
ment with the carrier, clutch controlled means for shifting the endless carrier actuating member, said hoisting connection being anchored at one end, means engaging the opposite end of the hoisting connection for manipulating the same and including a clutch controlled winding drum and a brake, and endless flexible control lines having connections with the said clutches and with the said brake, and extending along the path of movement of the carrier whereby movement of the carrier and of the article engaging member may be manually controlled at various points in the length of movement of the carrier.

6. A conveyor apparatus including an elevated horizontally movable carrier having

article engaging means movable therewith and shiftable vertically with respect thereto, means for moving said carrier, means for shifting said article engaging means, and manually actuated means for independently controlling said moving and shifting means, consisting of endless flexible controlling connections extending along the path of movement of the carrier, said controlling connections having their major portions elevated and having a plurality of depending portions at spaced points in their length, for the purpose described. 25
30

In testimony whereof I have affixed my signature.

HARRISON M. BRIGHTMAN.
